COMBINED RAILING POST AND BRACKET

Leo J. Meyers, Murraysville, Pa.

Filed Aug. 12, 1959, Ser. No. 57,150

Term of patent 14 years

(Cl. D13—7)

Figure 1 is a front elevational view of the essential portion of the combined railing post and bracket shown in Figure 6.

Figure 2 is a side elevational view thereof;
Figure 3 is a rear elevational view thereof;
Figure 4 is a top plan view thereof;
Figure 5 is a front perspective view thereof; and
Figure 6 is a front perspective view of a combined railing post and bracket showing my new design.

I claim:

The ornamental design for a combined railing post and bracket, as shown and described.
